UNITED STATES PATENT OFFICE.

GEORGE W. WHIPPS, OF HOPKINS, MINNESOTA.

HEATER.

Application filed October 11, 1926. Serial No. 140,910.

This invention relates to heating devices for motor vehicles and the primary object is to provide a simple, practical and efficient attachment whereby the heat emanating from the customary muffler of the exhaust pipe may be conveniently utilized for heating the interior of the car. A further object is to provide a heater which can be very quickly and easily installed, and which may be installed without first removing or changing the muffler, or in any way altering or disfiguring the car, except for the making of a hole in the floor board, through which the heater pipe is projected from the heater shell proper. Further and more specific objects will be disclosed in the course of the following specification, reference being had to the accompanying drawing, in which:

Fig. 1 is a perspective view of the heater, before being secured in place.

Fig. 2 is a central sectional elevation through the heater and also showing parts of an automobile to which it is attached.

Fig. 3 is a front elevation of the heater shown in Fig. 1.

Referring to the drawing more particularly and by reference characters A designates the floor of a motor vehicle having a seat B, a muffler C, and the exhaust pipe D, which connects the muffler with the exhaust manifold of the engine (not shown) all being of common and well known construction and arrangement.

The heater consists primarily of a shell 4, which surrounds the muffler C and extends, with its front end, forwardly thereof. The shell is longitudinally split at its under side where it has two overlapping edges 5, so that it may be opened to drop over the pipe D, after which it is moved back over the muffler, as shown in Fig. 2. The rear end of the shell 4 is tightened about the rear end of the muffler shell, and is there secured by a clamping strap 6 having a bolt 7. Similarly the forward portion of the shell 4 is provided with a clamping strap 8 having a bolt 9. One of the flanges 5 has a lip 10, for engagement with the adjoining flange, and thus prevents the forward end of the shell from being clamped by 8-9, to less than a predetermined diameter. The normal front end diameter of the heater shell is greater than the normal rear diameter, with a result that the shell is rearwardly tapered, and provides a rearwardly tapering annular passage between itself and

the muffler, and this passage is utilized for the heating of the air, by the muffler body, as it passes to the car body.

The substantially cylindrical portion of 60 the heater, forward of the muffler, is provided with an inclined deflector plate 11, which is elliptical, in plan, so as to fit snugly in the embossed rim 12 of the shell. This plate is preferably made in two sections, secured together as at 13, so that it may be secured over the pipe D without removing the muffler, and is of course provided with a central elliptic aperture 14, to accommodate the pipe D. Directly above the plate 11, the heater shell 4 is provided with an opening up through the floor A of the car. The upper end of the pipe 16 is provided with a damper 17, of any common and well known construction, for regulating the quantity 75 of warm air into the car.

The lower end of the deflector plate 11 is horizontally cut, as at 18, so as to provide a segmental opening 19, through which the incoming or cold air passes.

The construction and method of installing the heater should now be clear. The use or operation may be briefly described, as follows: As the car moves forward the cold air striking the deflector plate 11 is directed 80 downwardly and rearwardly to the opening 19, and from it is swept rearwardly and about the muffler by which it becomes heated. It then passes forwardly and up through the pipe 16 and damper 17 to the interior 85 of the car.

It is understood that suitable modifications may be made in the general design and structural details of the invention as herein shown and described, provided, however, 90 that said modifications come within the spirit and scope of the appended claims.

Having now therefore fully shown and described my invention, what I claim to be new and desire to protect by Letters Patent 100 is:

1. A heater for a motor vehicle having an exhaust pipe and a muffler at the rear end thereof, comprising a shell surrounding the muffler and extending forwardly thereof, 105 an inclined deflector plate arranged within the forwardly extended portion of the heater shell and forming with said shell a heating chamber, and having an air inlet at a rearward point into said chamber, and a pipe 110 connecting the shell with the floor of the car.

2. A heater for a motor vehicle having an

exhaust pipe and a muffler at the rear end thereof, comprising a longitudinally split shell, a clamping band for securing the rear end of the shell about the rear end of the muffler, the shell being wider toward its other end so as to form a tapering annular passage between itself and the body of the muffler, a deflector in said other end of the shell for directing incoming air into the lower end of the passage, and a pipe connecting the upper part of the shell with the body of the vehicle.

3. A heater for a motor vehicle having an exhaust pipe and a muffler at the rear end thereof, comprising a longitudinally split shell, a clamping band for securing one end of the shell about one end of the muffler, the shell being wider toward its other end so as to form a tapering annular passage between itself and the body of the muffler, a deflector in said other end of the shell for directing incoming air into the lower end of the passage, a second clamping band about an intermediate portion of the shell and being operative to assist in holding the deflector in place, and means for directing heated air from the shell into the vehicle.

4. A heater for a motor vehicle having an exhaust pipe and a muffler at the rear end thereof, comprising a longitudinally split shell, a clamping band for securing one end of the shell about one end of the muffler, the shell being wider toward its other end so as to form a tapering restricted passage between itself and the body of the muffler, a deflector in said other end of the shell for directing incoming air into the lower end of the passage, a second clamping band for securing said deflector plate in the shell, and means for directing heated air from the shell into the vehicle, said shell having an elliptical groove for receiving the deflector plate.

5. A heater for a motor vehicle having an exhaust pipe and a muffler at the rear end thereof, comprising a longitudinally split shell, a clamping band for securing the rear end of the shell about the rear end of the muffler, the shell being wider toward its other end so as to form a tapering annular

passage between itself and the body of the muffler, a deflector in said other end of the shell for directing incoming air into the lower end of the passage, and a pipe connecting the upper part of the shell with the body of the vehicle, said deflector plate having an opening through which said incoming air may pass.

6. A heater for a motor vehicle having an exhaust pipe and a muffler at the rear end thereof, said heater comprising a tapered shell the rear portion of which surrounds the muffler so as to form an annular heating chamber thereabout, said shell extending beyond the forward end of said muffler to form an air passage, a deflector member in the forward end of the shell for directing air into the lower portion of the passage, and means for delivering heated air from the air passage into the vehicle, said deflector member having a central aperture for receiving the exhaust pipe.

7. A heater for a motor vehicle having an exhaust pipe and a muffler at the rear end thereof, said heater comprising a tapered shell the rear portion of which surrounds the muffler so as to form an annular heating chamber thereabout, said shell extending beyond the forward end of said muffler to form an air passage, a deflector member in the forward end of the shell for directing air into the lower portion of the passage, and means for delivering heated air from the air passage into the vehicle, said deflector member being sectionally formed so as to facilitate securing it about the exhaust pipe.

8. A heater of the character described comprising a rearwardly tapering shell, the same being longitudinally split so as to be adjustable in diameter, a pair of clamping bands about the shell, an inclined deflector plate, having a central opening, secured in the forward end of the shell, a warm air delivering pipe extending from the shell, directly above the deflector plate, said deflector having an opening at its rear end for the introduction of cold air into the heater shell.

In testimony whereof I affix my signature.
GEORGE W. WHIPPS.
